US0D1037188S

(12) **United States Design Patent** (10) Patent No.: **US D1,037,188 S**
 (45) Date of Patent: ** Jul. 30, 2024

(54) **SINGLE GANG ELECTRICAL DEVICE ENCLOSURE**

(71) Applicant: **NSi Industries, LLC**, Huntersville, NC (US)

(72) Inventor: **Allen John Ustianowski**, Denver, NC (US)

(73) Assignee: **NSi Industries, LLC**, Huntersville, NC (US)

(**) Term: **15 Years**

(21) Appl. No.: **29/820,472**

(22) Filed: **Dec. 22, 2021**

(51) LOC (14) Cl. **13-02**

(52) U.S. Cl.

USPC **D13/184**

(58) **Field of Classification Search**

USPC D13/107, 110, 118, 123, 133, 152–154, D13/173, 184, 199, 139.1, 139.3

(57) **CLAIM**

The ornamental design for a single gang electrical device enclosure, as shown and described.

DESCRIPTION

FIG. 1 is a front perspective view showing my new single gang electrical device enclosure design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depict portions of the single gang electrical device enclosure that form no part of the claimed design.

1 Claim, 7 Drawing Sheets
